UNITED STATES PATENT OFFICE.

CHARLES M. HEETER AND COLONEL C. HEETER, OF BUTLER, PENNSYLVANIA; SAID COLONEL C. HEETER ASSIGNOR TO SAID CHARLES M. HEETER.

PACKER FOR DEEP WELLS.

SPECIFICATION forming part of Letters Patent No. 747,321, dated December 15, 1903.

Application filed May 11, 1903. Serial No. 156,613. (No model.)

To all whom it may concern:

Be it known that we, CHARLES M. HEETER and COLONEL C. HEETER, of Butler, Butler county, Pennsylvania, have invented a new and useful Packer for Deep Wells, of which the following is a full, clear, and exact description, reference being had to the accompanying drawings, forming part of this specification, in which—

10 Figure 1 is a longitudinal section of our improved packer in position in the well, showing the parts before expanding the rubber. Fig. 2 is a view similar to Fig. 1, showing the packer expanded in place. Fig. 3 is a bottom plan view of the expansible metallic ring we employ in contracted position. Fig. 4 is a vertical section of the same when expanded. Fig. 5 is a side elevation of the ring when expanded with the holding-band broken 20 away. Fig. 6 is a bottom plan view, partly in horizontal section. Fig. 7 is a detail view showing a joint of the expansible ring. Fig. 8 is a side elevation of the form of Fig. 1, showing the upper portions of the casing; and 25 Figs. 9 and 10 are views similar to Fig. 1, showing modified forms.

Our invention relates to that class of packers wherein a flexible gasket of rubber or similar material is expanded against the casing or wall of the well by the weight of the casing bearing upon the upper end of the rubber; and the object of the invention is to protect one or both ends of the gasket and to prevent leakage of gas around the upper portion of the rubber collar and outside and around the ring or abutment which bears on it, also to enable a relatively smaller packer to be used.

Heretofore in this class of packers a rigid 40 non-expansible collar or abutment has been used on the casing which rested on the top of the rubber gasket and caused it to bulge out under the weight of the superimposed tubing or casing; but in such cases the rubber when 45 expanded projected beyond the external diameter of the abutment; and hence as the outer part of the rubber was not backed up by metal the gas was liable to be forced past the rubber and around the abutment. More- 50 over, the rubber would be squeezed around

the abutment and become injured and gradually deteriorated. Our invention overcomes these difficulties; and it consists in providing an expansible metallic ring which bears upon the end of the rubber gasket and which is 55 expanded when the rubber is swelled out. The rubber is thus backed up at all times and leakage is prevented.

It also consists in providing means for expanding the metallic ring when the rubber is 60 expanded.

In the drawings, referring to the form of Figs. 1 to 7, inclusive, 2 represents a lower section of the casing or tubing of the well, which is connected by a double screw-plug 3 65 with a collar 4, having its lower end of conical shape on the exterior, as shown at 5. The packer-shell 6 is screwed into the interior of the collar 4, and the rubber gasket 7 surrounds the shell and rests at its lower end on a ring 70 8, which is screwed to the lower section 9 of the casing or tubing. The shell 6 is arranged to slide through the collar 8 and carries a ring 10, which guides it within the casing 9. At the upper end of the rubber gaskets and 75 around the shell 6 of the packer is placed our expansible ring 11, which when contracted is approximately of the size of the rubber gasket. The inner face of ring 11 is preferably beveled or inclined to allow easy 80 entrance of the cone.

We have shown the packer as an anchor-packer—that is, one where the casing or tubing extends to and rests on the bottom of the hole to give the resistance for swelling the 85 rubber at the slip-joint; but the invention may be applied to either an anchor-packer or to a wall-packer where the casing extends down to the packer only and where the resistance is formed against the wall of the 90 well near the packing-point. In this form when the packer is placed at the proper point in the string of the casing and the casing is lowered to the bottom of the well the weight of the superimposed casing will force the 95 packer-shell down through the rubber, the conical end of the collar 4 being forced into and through the metallic ring 11 to expand it and then passing within the rubber gasket. The abutment on the sleeve 3 then 100

bears on the metallic ring 11 and by the weight of the casing will swell out the rubber and effectually pack the well.

Different forms of the expandable metallic ring may be used, though we prefer the form shown in detail in Figs. 3 to 7. In this form the ring consists of a plurality of arc-shaped segments 12, each having an outwardly-projecting arc-shaped flange 13 at the top and a similar flange 14 at the bottom. The ends of these flanged portions are preferably beveled or curved at the bottom, as shown at 15 in Fig. 3, in order to prevent cutting of the rubber on which they rest. The edges of these sections are in contact when the ring is in contracted position, and the parts are held in place by a spring-ring 16, which consists of a split band of steel fitting between the top and bottom flanges and around the outer curved faces or sections. In order to cover the joints between the sections and prevent dirt from getting into the recesses, we preferably extend the flanges 13 and 14 at one end of each section, these extensions 13' and 14' fitting in corresponding recesses in the next section. As the sections are expanded these flanges will still cover the joints and prevent their becoming clogged with sediment, and in order to make all the sections expand evenly and equally we preferably form depending pins 17, which project down from the top overhanging portions 13' and move within the groove or cut-away part of the next section. By the use of these pins the pressure upon any section will be distributed between all the sections, so that as the cone is forced into the ring its different portions will move out evenly and give an even expansion of the parts. When the device is to be unpacked, the casing is drawn up, the cone is pulled out of the expandable ring, the split ring in the rubbers contracts, and the device may then be pulled out.

In Fig. 8 we show the packer of Fig. 1, together with a portion of the casing above the packer. In a portion of the casing above the packer we preferably insert an outer collar 18, which is screwed to the top of one section and receives within it a lead gasket 19. The upper end of the collar hangs on an angular shoulder of the next upper section, and when the weight of the casing is brought on the parts the section 20 will be forced down against the lead gasket, thus compressing and sealing it. We have also shown the section 20 as cut in two pieces and provided with a strainer 21 between them, a collar 22 securing the parts in place with the strainer between.

In Fig. 9 we show another form of the invention, wherein the ring and cone are at the lower end of the expandable gasket. In this form the abutment or plug 3^a rests upon the upper end of the gasket 7^a, and the cone 4^a is secured to the lower end of the shell 6^a. The expandable metal ring 11^a is at the lower end of the gasket and rests upon a collar 23,

which is screwed to the next section 24. In this form the ring 10^a rests against the lower end of the ring 23 and is screwed to the sleeve 25, which in turn is screwed to the interior of the cone 4^a. In this case when the resistance is formed and the packer lowered the cone will expand the ring 11^a, while the weight of the casing on the abutment 3^a forces out the rubber.

In Fig. 10 we show a double form, wherein an upper cone 4^b and a lower cone 4^c are used, the upper one being similar to that of Fig. 1 and secured to the ring 3^b. The upper expandable ring 11^b rests against the upper end of the gasket 7^b, while the lower expandable ring 11^c rests upon a ring 23^a, secured to the lower section 24^a of the casing. The lower cone 4^c may slide upon the inner shell 6^b of the packer or may be secured thereto. In this form when the casing is lowered the two cones will force out the two expandable rings, while the upper ring 3^b will press down upon the upper expandable ring 11^b and force out the rubber, the lower end of the rubber resting upon the ring 26, which is formed as a part of the lower cone 4^c. This ring 26 will rest on the lower expandable ring after the lower cone has entered and expanded it.

The advantages of our invention result from the use of the expandable metal ring resting against the end of the gasket. This ring prevents injury to the gasket, stops any liability to leakage, and also enables a packer having a normally smaller diameter to be used than could otherwise be employed. In ordinary packers their size must be nearly that of the hole in order to pack efficiently when lowered to the proper position, and on account of irregularities in the shape and size of the hole in its different parts such packers are very liable to stick while lowering. By using the expandable ring a smaller packer in proportion to the size of the hole may be used than could otherwise be employed, thus greatly lessening the liability to sticking during lowering.

Many variations may be made in the form and arrangement of the packer, the expandable ring, the mechanism for forming resistance, &c., without departing from our invention.

We claim—

1. A packer for deep wells having a flexible annular gasket, an expandable metal ring resting against the end of the gasket, and mechanism for expanding the gasket and ring; substantially as described.

2. A packer for deep wells having an annular gasket of rubber or similar material, a metallic expandable ring resting against one end thereof, and a cone and abutment arranged to expand the gasket and ring; substantially as described.

3. A packer for deep wells having an expandable gasket and an expandable metal ring resting against one end thereof, said ring be-

ing composed of a plurality of sections, and a resilient ring arranged to normally hold them in contracted position; substantially as described.

5 4. A deep-well packer having an expandible gasket, and an expansible metallic ring resting against its end, said ring having a plurality of sections with cover-pieces at the joints; substantially as described.

10 5. A deep-well packer having a shell, an expansible gasket around the shell, an expansible metallic ring surrounding the shell

and resting on the top of the gasket, and an abutment and cone secured to the shell extension and arranged to expand the gasket 15 and metal ring; substantially as described.

In testimony whereof we have hereunto set our hands.

CHARLES M. HEETER.
COLONEL C. HEETER.
